UNITED STATES PATENT OFFICE.

AUGUST F. KAUFMAN, OF WHEELING, WEST VIRGINIA.

PACKAGE-TIE AND ADVERTISING DEVICE COMBINED.

1,233,365.

Specification of Letters Patent.

Patented July 17, 1917.

Application filed March 7, 1917. Serial No. 153,153.

To all whom it may concern:

Be it known that I, AUGUST F. KAUFMAN, a citizen of the United States of America, and resident of Wheeling, county of Ohio, 5 and State of West Virginia, have invented certain new and useful Improvements in Package-Ties and Advertising Devices Combined, of which the following is a specification.

10 This invention relates broadly to fastening members, and more particularly to a cord-gripping package-tie; and it has for its primary object to provide an extremely simple, inexpensive, efficient and conveniently handled form of fastener whereby the opposite ends of a cord used in wrapping packages may be securely held.

15 A further object is to provide a device of the character mentioned which embodies, in association with a cord fastening member, means whereby said member is supported in a position wherein its ends are disposed in convenient cord-receiving position.

20 Another object within the contemplation of the invention is to provide a device of the character mentioned adapted for carrying advertising matter or the like.

25 In describing the invention in detail, reference is herein had to the accompanying drawing, in which—

30 Figure 1 is a perspective view of a package, illustrating the application of the invention;

35 Fig. 2 is a central longitudinal section of the invention;

Fig. 3 is a plan view of a modified form designed as a bag fastener; and—

Fig. 4 is a modification designed as a package tie and carrying handle.

40 Referring to said drawings, 1 indicates a body member composed of metal, preferably wire, the same having its opposite ends turned back to occupy positions in overlying relation thereto, forming terminal hooks 2.

45 Disposed between said hooks 2 and resting upon said body member 1 is a flat plate 3 which may be composed of cardboard or of any other suitable material and which may have a circular, rectangular, or any other preferred form. Said plate is preferably

50 provided with notches or recesses 4 in opposite edges thereof for the reception of the plate-engaging portions of said hooks, as is clearly shown in Fig. 2, said plate being sprung into position so that said portions

will seat in said recesses for preventing chance separation of the parts.

The hook terminals are spaced from the straight body member 1 a distance slightly in excess of the thickness of the plate 3, so 60 that slit-like cord-receiving spaces 5 of suitable width are afforded between the seated plate and said terminals, as shown in Fig. 2.

As is obvious, the device is adapted for securing the opposite ends of a cord 6 which 65 is passed about the package in one direction, but it is preferably used as shown in Fig. 1 wherein the cord is shown passed once around the package in one direction and then passed around the package in a direction 70 at right angles to the first pass. In practice, the device is laid flat upon a face of the package with its hook terminals disposed in overlying relation to the plate 3. Then, holding the plate by firmly pressing 75 thereon with the thumb of one hand, one end of the cord is drawn into closely gripped position between the face of said plate and one of said hook terminals, after which said cord is passed around the package and is 80 again drawn into engagement with said terminal, whence the cord is passed around the package in a direction at right angles to the first pass; and, finally, the free end of the cord is drawn into closely gripped relation 85 to the other of said hook terminals.

The plate 3 not only serves to maintain the wire in a position wherein its hook terminals are disposed uppermost and are, therefore, readily engageable, but it serves 90 as a means whereby the device may be readily held by hand in a stationary position during the cord-applying operation. Furthermore, said plate is admirably suited for carrying a dealer's name and address or 95 other advertising matter.

In the modification shown in Fig. 3 a wire is shaped to form a body member 1^a of arcuate, or substantially semi-circular, form and terminal hooks 2^a, the latter being 100 turned outwardly and back into closely approaching relation to the body 1^a to form slits 5^a for receiving the ends of a cord 6^a, said device being designed as a tie for bags, as grain or cement bags.

105 In the modification illustrated in Fig. 4 a portion of the body of the wire located intermediate the hooks 2^b is bent to form an upstanding bail 1^b which is elevated above the plane of the lower package-engaging 110

portions of said hooks to provide a handle whereby the package may be carried. The plate 3^b received between the hooks 2^b is provided with a longitudinal slot 7 through 5 which the bail is projected, as shown.

What is claimed is—

1. A package-tie comprising a body portion having integral hooks formed at opposite ends thereof, and a plate seated upon 10 said body portion between said hooks, the terminals of said hooks being disposed in overlying relation to the ends of said body portion and being spaced away from the latter a distance greater than the thickness 15 of said plate.
2. A package-tie comprising a wire shaped to form a body portion and hook terminals at the opposite ends of said body portion, said hook terminals being disposed in overlying relation to said body portion, and a 20 plate having notches in opposite edges thereof mounted upon said body portion between said hooks and having the latter received in said notches, said terminals being spaced

from said body portion to form cord-receiving slits between them and the upper face 25 of said plate.

3. A package-tie comprising a wire having its ends shaped to form oppositely disposed hooks the under sides of which are designed to seat upon a package, said wire having a portion thereof intermediate said hooks bent to form a bail-like handle which occupies an elevated position above the level of said hooks, and a plate seated upon said wire and having opposite edges thereof received between said hooks and in underlying 30 relation to the terminals of the latter, said plate having a slot therein intermediate its 35 said opposite edges through which said bail 40 is projected.

In testimony whereof, I affix my signature in presence of two subscribing witnesses.

AUGUST F. KAUFMAN.
